UNITED STATES PATENT OFFICE.

WILLIAM TURNBULL, OF PEORIA, ILLINOIS, ASSIGNOR TO CATERPILLAR TRACTOR CO., OF SAN LEANDRO, CALIFORNIA, A CORPORATION OF CALIFORNIA.

ICE GROUSER SHOE.

Application filed June 8, 1927. Serial No. 197,328.

My invention relates to grousers or shoes adapted to be attached to the track of a crawler or track-layer type vehicle and relates particularly to a grouser for adapting 5 such a vehicle for use on ice, and comparable slippery surfaces.

An object of my invention is to provide a grouser shoe which will afford excellent traction for a crawler type vehicle on ice and 10 similar slippery surfaces.

Another object of my invention is to provide a grouser shoe which will permit the passage therethru of snow and slush from the interior of the track.

15 A further object of my invention is to provide a light weight grouser shoe which carries a plurality of ground engaging surfaces.

My invention possesses other advantageous 20 features, some of which with the foregoing, will be set forth at length in the following description where I shall outline in full that form of the ice grouser shoe of my invention, which I have selected for illustration in the 25 drawings accompanying and forming part of the present specification. In said drawings I have shown one form of ice grouser shoe embodying my invention, but it is to be understood that I do not limit myself to such 30 form since the invention, as set forth in the claims may be embodied in a plurality of forms.

In the drawings:

Fig. 1 is an end elevation of the ice grouser 35 shoe of my invention as attached to the track of a crawler type vehicle.

Fig. 2 shows in plan the ice grouser shoe of my invention as seen from below.

Fig. 3 is a side elevation of the ice grouser 40 shoe of my invention as attached to a track.

Fig. 4 shows the ice grouser shoe of my invention in transverse section, the plane of section being indicated by line 4—4 of Fig. 2, and the grouser shoe being attached to a 45 link of a track.

The ice grouser shoe of my invention preferably comprises a unitary structure having longitudinal and transverse ice grousers thereon and provided with a central opening thru which snow and slush can be discharged from the track.

A standard type of track to which the ice grouser shoe of my invention is adapted to be attached comprises a plurality of links 6 55 joined by bushings 7 and track bolts 8 and

each link generally includes a flange 9 apertured to receive fastening means, such as a nut and bolt 11 for the attachment of track shoes. To a link such as 6, I preferably attach my ice grouser shoe which preferably is 60 constructed of a single body of metal, either cast or drop forged. The grouser shoe preferably includes a pair of pads 12 symmetrical- 65 ly situated at either side of a center line and provided with apertures 13 for alignment with the apertures in flange 9 to receive the fastening means 11. The two pads 12 are connected by transverse bars 14 and 16, re- 70 spectively, which merge smoothly with the pads and together with them bound a central 75 opening 17 thru which snow and slush can be discharged by the track.

Located on the transverse bar 14 and pref- 80 erably coinciding with the center line of the 75 grouser shoe is an upstanding longitudinal flange 18 of generally triangular section which is intended to engage the ground and 85 may be sharpened for better traction on ice. At the edge of opening 17 and at one end of flange 18 a pair of supporting shoulders 80 19 are formed. They reinforce the longi- 90 tudinal flange 18 and greatly increase its strength. Along the other transverse bar 16, a transverse flange 21 is provided which along 95 one edge is perpendicular to the upper sur- 85 face of the grouser shoe and along the other edge lies at an angle to the lower surface of the grouser shoe and merges smoothly therewith. A pair of enlargements 22 are 100 formed intermediate the ends of transverse flange 16 and project from the pads 12 sub- 90 stantially the same amount as does flange 18. The enlargements can also be sharpened for engagement with ice and aid materially in in- 105 creasing the traction on slippery surfaces.

Joining flanges 16 and pads 14, are a pair 100 of reenforcing webs 23 projecting from pads 12 and lying substantially perpendicular thereto at the rim of opening 17. A very strong grouser shoe is therefore provided. The transverse bar 16 intermediate the en- 105 largement 22 and at the intersection of the flange with the surface contacting the track shoe 9, is relieved by a cut which provides a slanting surface 24.

By employing the foregoing construction, I have provided an ice grouser shoe which 110 grips the ice especially well due to flanges 18 and 21 and is amply reenforced by webs 23 and shoulders 19. It is also provided with a

central aperture 17 thru which snow and slush can be discharged from the track and it can readily be bolted into place and removed from the track shoes 6.

5 I claim:

1. An ice grouser shoe comprising an integral body including a pair of pads, a pair of transverse bars connecting said pads, reinforcing webs on said pads connecting said 10 bars, a longitudinal flange on one of said bars, and a transverse flange on the other of said bars.

2. An ice grouser shoe comprising a pair 15 of pads, each of said pads having an aperture therein, a pair of transverse bars joining said pads and enclosing a central opening therewith, a longitudinal flange upstanding

from one of said bars, a transverse flange upstanding from the other of said bars, and a pair of enlargements on said transverse 20 flange.

3. An ice grouser shoe comprising a pair of pads, each of said pads having an aperture therein, a pair of transverse bars joining said pads and enclosing therewith a central opening, a reinforcing web on each of said pads connecting said bars, a longitudinal flange on one of said bars, supporting shoulders for said flange, a transverse flange on the other of said bars, and enlargements on said 25 flange adjacent said webs.

In testimony whereof, I have hereunto set my hand.

WILLIAM TURNBULL
